DIE ASSEMBLY FOR FORMING HOLLOW
METAL ARTICLES

Frans B. Wendel, Long Island City, N. Y.

Application May 11, 1937, Serial No. 141,936

1 Claim. (Cl. 113—44)

This invention relates to an improvement in die assemblies and particularly to die assemblies for forming hollow metal articles.

One of the objects of the present invention is to provide a superior die assembly of the character referred to which may be produced at a low cost for manufacture.

A further object is to provide a superior die assembly in which the component units may be readily opened and closed.

Another object of the present invention is to provide a superior die assembly for forming hollow metal articles in which various die units may be interchangeably assembled to thus provide for the economical production of various sizes of a given type of hollow metal article.

A still further object is to provide superior means for holding in assembled relationship the component units of a die assembly for forming hollow metal articles.

With the above and other objects in view, as will appear to those skilled in the art from the present disclosure, this invention includes all features in the said disclosure which are novel over the prior art and which are not claimed by me in a separate application.

In the accompanying drawings, in which certain modes of carrying out the present invention are shown for illustrative purposes:

Fig. 1 is a broken view mainly in front elevation and partly in vertical section showing a portion of a power press and a die assembly therein suitable for producing wrought-metal pipe-Ts, the units of the die assembly being shown in their closed and locked positions;

Fig. 2 is a horizontal sectional view taken on the line 2—2 of Fig. 1 but showing the die assembly in plan;

Fig. 3 is a vertical transverse sectional view taken on the line 3—3 of Fig. 1;

Fig. 4 is a vertical longitudinal sectional view taken on the line 4—4 of Fig. 2 but on a slightly reduced scale and showing the die assembly opened;

Fig. 5 is a perspective view of the die assembly of the preceding figures with one of the guide-dies shown detached and in vertical longitudinal section;

Fig. 6 is a view mainly in side elevation and partly in vertical central section of the second stage T blank;

Fig. 7 is a similar view of the third-stage T blank;

Fig. 8 is a corresponding view of the fourth-stage T blank;

Fig. 9 is a similar view of a finished T;

Fig. 10 is a perspective view of another deflecting-die unit which may be used, and is shown in conjunction with, the same guide-die units which are illustrated in Fig. 5, to produce a reducing-T blank like that shown in Fig. 11;

Fig. 11 is a perspective view partly in section of a reducing-T;

Fig. 12 is a view partly in front elevation and partly in vertical central longitudinal section illustrating a die assembly for the production of elbows;

Fig. 13 is a top or plan view thereof;

Fig. 14 is a broken view thereof in end elevation; and

Fig. 15 is a view partly in side elevation and mainly in central longitudinal section of an elbow which may be produced by the die assembly of Figs. 12 to 14 inclusive.

The embodiment of the present invention here-
in chosen for illustration in Figs. 1 to 5 inclusive, includes a vertically-shiftable die-unit 20, which for convenience of description may be designated as a "deflecting-die unit". In its upper face, the said unit 20 is formed with three (more or less) longitudinal deflecting-grooves 21—21—21, which in the instance shown are of semicircular form in cross-section to accommodate the lower half of the "run" portion of a sheet-metal T. At the respective opposite ends of each of the deflecting-grooves 21 is installed a removable cylindrical stop-abutment 22 for the purpose as will hereinafter appear.

At each of its respective opposite ends, the deflecting-die unit 20 is formed with an upwardly-facing stop-rib 23, the upper face of each of which is adapted to engage with the under-face of a stop-rib 24, one of which latter is formed upon each of two complementary retaining-bars 25 rigidly attached to the die-bed 26 of a power press, generally designated by the numeral 27.

The power press 21, above referred to, may be of any approved type and requires no detailed description herein other than to say that it includes two upright frame-members 28—28, between which is guided, with capacity for vertical reciprocation, an outer plunger-head 29, and within which latter is mounted a second or inner plunger-head 30 capable of independent vertical movement with respect to the said outer plunger-head 29.

In its under-face, the deflecting-die unit is formed with a plurality of downwardly-opening spring-pockets 31 into each of which fits the up-

per end of a helical releasing-spring 32 having its lower end seated in the aligned one of a plurality of upwardly-opening spring-pockets 33 formed in the upper face of the die-bed 26. The 5 said releasing-springs exert a constant effort to lift the deflecting-die unit 20 upwardly to engage the upper face of the stop-ribs 23-23 of the said unit with the under-face of the stop-ribs 24-24 upon the inner faces of the retaining-bars 25-25.

Mounted upon the upper face of the deflecting-die unit and movable longitudinally therewith is a pair of complementary guide-die units 34 and 35, each of which is formed along its 15 lower front and rear corners with a depending guide-rib 36-36 fitting into longitudinal guide-grooves 37-37 formed in the upper front and rear corners respectively of the deflecting-die unit 20.

20 Each of the guide-die units 34 and 35 is formed in its under-face with three (more or less) horizontal grooves 38-38 of semicircular form in cross-section and registering with the similarly-shaped deflecting-grooves 21 in the deflecting-die unit 20, so as to form in conjunction therewith three parallel cylindrical recesses on each of the respective opposite sides of the vertical transverse center of the said unit 20. Intersecting each of the horizontal grooves 38 in the guide-die units 34 and 35 is a vertical guide-groove 39, three of which latter are formed in the inner abutting faces 40 of the said units 34 and 35, as especially well shown in Fig. 5.

The vertical guide-grooves 39, above referred to, 35 in the guide-die units 34 and 35 are also of semicircular form in cross-section and each is connected at its lower end to the inner end of a complementary horizontal groove 38 by a rounded portion 41. When the three die-units 20, 34 and 35 40 are in their closed positions, as illustrated in Figs. 1, 2 and 3, the vertical guide-grooves 39 of the unit 34 form in conjunction with the similar but oppositely-opening grooves of the unit 35, a vertically-extending cylindrical guide-passage which 45 intersects at its lower end the central portion of a horizontal passage, also of cylindrical form in cross-section, and the lower half of which is formed by the deflecting-grooves 21 in the unit 20 and the upper half of which is formed by the mating horizontal grooves 38 in the respective under faces of the guide-die units 34 and 35.

As will be noted by reference to Figs. 1, 2 and 3 in particular, two opposed guide-bars 42-42 are secured to the upper face of the die-bed 26 and 55 accommodate between them the deflecting-die unit 20 and the lower portions of the guide-die units 34 and 35. Carried by each of the guide-bars 42-42 is a stop-bar 43, the under-surface of which is adapted to be engaged by the upper 60 face of a longitudinal stop-rib 44, one of which latter is formed upon the respective front and rear faces of each of the guide-die units 34 and 35 adjacent the lower edge thereof.

The lower left corner of the guide-die unit 34 65 is formed with a bevel or locking-cam surface 45 which is adapted, when the die-units are closed and locked as shown in Figs. 1 to 3 inclusive, to engage with a similarly-sloping bevel or locking-cam surface 46 formed at the upper right corner of the left-hand retaining-bar 25. Similarly, the lower right corner of the guide-die unit 70 35 is formed with a bevel or locking-cam surface 47 engageable under the conditions just referred to with a similarly-sloped bevel or locking-cam

surface 48 formed at the upper left corner of the right-hand retaining-bar 25.

The upper portion of the left-end wall of the guide-die unit 34 and the upper portion of the right-end wall of the complementary unit 35 are 5 each slightly inclined off the vertical plane as shown to provide locking-cam surfaces 49-49 which are respectively engageable by similarly-sloping locking-cam surfaces 50-50 respectively formed upon two oppositely-arranged L-shaped locking-shoes 51-51 rigidly secured within a downwardly-opening recess 52 formed in the under-face of a die-locking member 53 rigidly attached to the under-face of the outer plunger-head 29 of the power press 27. 15

For the purpose of shifting the guide-die units 34 and 35 into their open and closed positions, each of the said units has projecting outwardly from its outer face an eye-member 54 which extends, with freedom for slight vertical movement, 20 into the notch in the bifurcated forward end 55 of an operating-lever 56 oscillating in a horizontal plane upon a stud 57 mounted in the frame of the power press 27. The forward end of each of the two operating-levers 56 is loosely 25 coupled to the adjacent one of the eye-members 54 by means of a vertical coupling-pin 58, and the respective rear ends of the said operating-levers are loosely connected by means of coupling-pins 59-59 to an operating-plunger 60 which reciprocates toward and away from the rear face of the die-assembly and which may be operated by any approved mechanism such, for instance, as by a hydraulic cylinder and piston. 30

Secured to the inner plunger-head 30 of the power press 27 are three corresponding plungers 61-61-61, spaced apart so as to respectively enter the three similarly-spaced guide-passages formed by the complementary vertical grooves 39 in the guide-die units 34 and 35 when the same 35 are in their closed position. Each of the plungers 61 is formed with a downwardly-facing annular thrust-shoulder 62 and with an L-shaped fluid-relief passage 63, the vertical reach of 40 which latter intersects the rounded lower end of 45 the plunger, and the relatively-short horizontal reach of which intersects the periphery of the plunger at a predetermined point below the thrust-shoulder 62.

In the operation of the mechanism above described, a test tube shaped blank 64 of copper or other suitable material is inserted between each of the opposed guide-grooves 39 in the guide-die units 34 and 35, while the same are separated as shown in Fig. 4 of the accompanying drawings. 55

The plunger 60 is now moved rearwardly to thus effect, through the intermediary of the operating-levers 56-56 and associated parts, the closure of the guide-die units 34 and 35. The outer plunger-head 29 is now caused to descend, 60 so that the opposed locking-cam surfaces 50-50 of the locking-shoes 51-51 seat against the locking-cam surfaces 49-49 of the guide-die units 34 and 35, to thus hold the said units against separation. The continued downward movement 65 of the outer plunger-head 29 and the parts carried thereby will depress both the now closed guide-die units 34 and 35 and the deflecting-die unit 20 against the counter-urge of the releasing-springs 32. The movement just referred to 70 will cause the locking-cam surfaces 45 and 47 respectively of the said units 34 and 35 to be firmly engaged with the locking-cam surfaces 46 and 48 of the retaining-bars 25-25. When the cam-surfaces 45 and 47 are respectively engaged with the 75

cam surfaces 46 and 48, as just described, the deflecting-die unit 20 will be firmly seated against the upper face of the die-bed 26.

The inner plunger 30 is now forced downwardly 5 so as to cause the reduced lower ends of the plungers 61 to enter the aligned first-stage blanks 64, which latter have been previously filled with oil or other suitable liquid. As the lower end of a given one of the plungers 61 enters the open 10 upper end of a first-stage blank 64, the fluid in the said blank will be forced outwardly from the relief-passage 63 until such time as the horizontal reach of the said passage is covered by the inner surface of the blank, whereupon hydraulic 15 pressure will be built up within the said blank, with the effect of slightly swelling its lower portion outwardly in opposite directions into the horizontal cavity in the die-assembly.

When in the continued downward movement 20 of the plungers, their thrust-shoulders 62 engage with the upper ends of the aligned blanks 64, the said blanks will be forced bodily downwardly in the vertical guide-passages of the die-assembly, in which the blanks are located, and 25 will be deflected outwardly to form embryonic T-shaped blanks 65, which latter for convenience of description may be designated as "second-stage" blanks.

The plunger-heads 29 and 30 are now retired 30 upwardly to the position in which they are indicated in Fig. 4, whereupon the deflecting-die unit 20 and the guide-die units 34 and 35 will be elevated by the springs 32 until checked by the stop-means already described. The plunger 60 35 is now moved forwardly toward the die-assembly to effect, through the intermediary of the operating-levers 56, the separation or opening of the guide-die units 34 and 35. The parts will now have assumed the positions in which they 40 are shown in Fig. 4.

The second-stage blanks 65 (three of which have been simultaneously formed) may now be removed from the now open die-assembly for the purpose of annealing the said blanks. Other second-stage blanks which have been previously annealed may be introduced between guide-die units 45 34 and 35, and the operation above described may be repeated to convert such second-stage blanks into blanks 66 of the character shown in Fig. 7, which blanks for convenience of description 50 may be designated as "third-stage" blanks. Three third-stage blanks, after being annealed, are introduced into the die-assembly, and the operation above described again repeated to simultaneously produce three blanks 67 of the character shown in Fig. 8, which blanks may 55 be designated as "fourth-stage" blanks. It will be noted that the fourth-stage blanks just referred to have the respective opposite ends of their "run" portions flattened out, so to speak, as at 68—68, by having been forced into engagement, during the last operation, with the inner ends of the cylindrical stop-abutments 22—22. It is preferred, during each successive 60 operation to convert a blank of one stage into a blank of the next stage, that the plunger 61 be replaced by similar but longer plungers.

The fourth-stage blank above referred to may 65 be converted into a finished T by a suitable trimming operation which will remove the end-walls 68—68 of its "run" portion and even up the upper terminal of its branch. If desired, and as indicated by broken lines 69 in Fig. 9, one or more of the three terminals of the T may be 70 expanded or bellmouthed.

Should it be desired to produce a reducing T such as 10 illustrated in Fig. 11, a deflecting-die unit 71 (Fig. 10) may be substituted for the deflecting-die unit 20 before described and placed in assembled relationship with respect to the 5 guide-dies 34 and 35. The said deflecting-die unit 71 corresponds in all essentials to the deflecting-die unit 20 but instead of being provided in its upper face with semi-cylindrical deflecting-grooves the said unit 71 is provided with 10 three (more or less) relatively deep deflecting-grooves 72 which in conjunction with the registering horizontal grooves 38 of the guide-die units 34 and 35 will laterally circumscribe a passage 15 which may be characterized as of generally oval form in cross-section.

The resultant T blank which may be produced by a die assembly comprising the units 34, 35 and 71 will be characterized by a branch 73 corresponding in diameter to the branches of 20 the blanks of Figs. 6 to 9 inclusive but having an oval run portion 74 (indicated by broken lines in Fig. 11) of much greater perimeter. The trimmed blank may now be shaped by any suitable tools to convert its substantially oval run 25 portion 74 into cylindrical form 75 as is indicated by full lines in Fig. 11.

By providing a die assembly which is divided in planes transverse to the plane of the T to be produced rather than dividing the dies in 30 a plane parallel with the flatwise plane of the T not only is interchangeability achieved but the various units may be accurately and economically produced. For instance, the deflecting-grooves 21 of the deflecting-die unit may be 35 conveniently produced by a simple milling operation and similarly both the horizontal and vertical grooves 38 and 39 of the guide-die units may be milled. Furthermore in forming the rounded portion or fillet 41 interconnecting the 40 adjacent ends of the grooves 38 and 39, the die-unit may be revolved about the axis of the said portion 41 so that a milling cutter will serve the purpose of producing this portion also, rather than requiring time-consuming and expensive 45 die-sinking operations which would be necessary were an angular recess to be formed all in one face of a die-block.

In Figs. 12, 13 and 14 of the accompanying drawings there is illustrated a die assembly for 50 producing sheet-metal elbows. The die assembly referred to includes an inverted T-shaped deflecting-die unit which comprises a base-block 75 and a vertical block 76 rigidly secured together by a suitable number of dowel-pins 77 and screws 78. The respective opposite vertical 55 walls of the vertical block 76 are each formed with a plurality of vertical guide-grooves 79 each of which is smoothly merged by an arcuate deflecting-groove 80 with a groove 81 formed in the upper face of the base-block 75. The grooves 79, 80 and 81 are in effect continuous and are all 60 of semicircular form in cross-section.

Fitting into the angular notch-like portions 65 provided on each of the respective opposite sides of the vertical block 76 is a guide-die unit 82 having a vertical guide-groove 83 which is smoothly merged by an arcuate groove portion 84 with a horizontal groove 85 formed in the underface of the unit 82. As illustrated in the 70 left portion of Figs. 12 and 13 the horizontal terminal of a given one of the three L-shaped channels provided by the mating grooves 79, 83, 80, 84, 81, 85 is blocked by a cylindrical stop-abutment 86 having in its inner face a hemispherical 75

recess 87. After having been filled with oil or the like, an initially test tube shaped sheet-metal blank 88 is displaced longitudinally by means of one of the plungers 89, until it seats in the recess 87 of the local stop-abutment 86.

The lower terminals of the right-hand series of L-shaped passages provided in the die assembly are blocked off by a plane-ended stop-abutment 90 and are being utilized as shown to 10 produce elbow blanks 91 of a stage more advanced than the blanks 88 shown to the left of Figs. 12 and 13. The blanks 91 are forced into the die cavity, after being suitably annealed and filled with fluid, by suitable plungers such as 92, 15 and are thus provided at their lower outer ends with flat integral end walls 93 which may be later removed to produce an elbow 94 of the character illustrated in Fig. 15. The elbow 94 may, if desired, have one or both of its respective 20 opposite ends expanded or bellmouthed as indicated by broken lines 95 in Fig. 15.

The guide-die units 82, 82 and the deflecting-die unit comprising the major parts 15 and 16 are provided with stop-ribs, locking-cam surfaces, etc., of the same general character as the die units of the preceding figures and bear corresponding reference characters.

The invention may be carried out in other spe-

cific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

A die-assembly for forming hollow metal articles comprising: three complementary die-units which together provide connecting laterally-closed guide- and deflecting-channels, two of said die-units being movable relatively toward and from one another and each having a sloping locking-surface; locking-means movable in a path transverse to the said path of movement of the said two die-units and straddling the latter, the said locking-means having sloping locking-surfaces engageable with the said sloping surfaces of the said two die-units to lock the latter against movement relatively away from one another; and the third die-unit engageable with both of the said two die-units and movably mounted to be shiftable in a path transverse to the said path of movement of said two die-units; and means for shifting said third die-unit.

FRANS B. WENDEL.
